STAPLE DRIVING MACHINE

Roy E. Peterson, Norwalk, Conn., assignor, by
mesne assignments, to The E. H. Hotchkiss
Company, Norwalk, Conn., a corporation of
Delaware

Application March 21, 1947, Serial No. 736,195

11 Claims. (Cl. 1—49)

1

This invention relates to a staple driving machine, particularly of the type wherein a spring is used to operate a staple driver and there is an operating lever to retract the driver and tension the spring, with an automatic release to release the driver for operation by the spring to drive the staple. This type of machine is sometimes called a tacker. In this type of machine as now generally constructed, the driver is connected to a reciprocal plunger having considerable weight, which operates with the driver and through its momentum to impart a sort of hammer blow to the staple. This weight, however, slows up the action and speed of the driver, and then after it has been gotten up to speed, some means must be provided to arrest the movement of this relatively heavy plunger. These are objectionable features, and due to the reduced speed of the driver in the driving operation of the staple, there is a tendency for the staple to buckle and not penetrate the work properly.

It is an object of the present invention to eliminate this weight or plunger on the staple driver and operate the driver directly from the spring, so that it is operated at a much greater speed than is possible with the weighted driver, and there is less difficulty in arresting movement of the driver at the completion of the driving operation. It has been found that the staples are driven better with a higher speed, and the penetration by the prongs of the staple is more readily effected by this increased speed than where, with slower speed, momentum is relied on to secure penetration and setting of the staples. A greater speed also reduces buckling of the staple prongs, as the higher speed doesn't give the prongs time to buckle. Direct operation of the driver without the weighted plunger tends to lightness of the mechanism as well as increased speed. In short, with this device much greater speed of the staple driver is effected than where weight or momentum is relied on, and as suggested, it has been found that increased speed gives better and more reliable setting of the staple.

It is also an object to provide an improved means for retracting the driver by action of the operating lever in placing the driver and tensioning the spring for the driving operation.

With the foregoing and other objects in view,

2

I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a vertical longitudinal section through the device;

Fig. 2 is a horizontal section substantially on line 2—2 of Fig. 1;

Fig. 3 is a front view with the front plate removed, the plane of the figure being substantially on line 3—3 of Fig. 1;

Fig. 4 is a detail vertical section substantially on line 4—4 of Fig. 1;

Fig. 5 is a detail section substantially on line 5—5 of Fig. 1;

Fig. 6 is a section of the upper portion of the device showing the operating lever and the releasable pawl at about the time it releases the staple driver;

Figs. 7 and 8 are inner and top views respectively of the guide plate at the front of the feed guide, and

Fig. 9 is a side elevation of the front end portion of the housing with the front plate removed but shown in dotted lines.

The machine as illustrated comprises a housing 10 including a pair of side plates 11, preferably stamped to form of sheet metal and enclosing an inner housing 12 of generally U-shaped cross section, comprising side members 13 at the inner side of the side members 11, and a front guide wall 14 connecting these side members 13. This front guide wall has vertical slots 15 and 16 for certain of the operating members, as will be later described. The side plates 11 have their upper edges turned inwardly to form the top of a hand grip as indicated at 17, and has an elongated slot 18, the edges of which are similarly turned in as shown at 19, forming flanges which provide the lower part of the hand grip.

Mounted in the lower part of the housing between the side members 11 is a staple guide bar 20 extending longitudinally of the machine. This is preferably substantially U-shaped in cross section, as shown in Fig. 4, for lightness and also to permit its being formed of a strip of sheet metal.

The side walls 11 are preferably inclined upwardly and outwardly, as shown in Fig. 4, so that when similarly shaped staples are on the bar and fed longitudinally thereof, they are held against rising off the bar. There is also preferably provided another guide bar 22 mounted between the side walls 11 and spaced above the top of the feed bar 20 sufficiently to permit feeding of the staples along the feed bar, but will form a top guide to help retain them on the feed bar. The bar 22 is also preferably of substantial U-shape as shown in Fig. 4, with the side flanges located at the inner sides of the side walls 11 and secured thereto by any suitable means, such as the transverse pins or rivets 23. The staple feed bar 20 is mounted on the lower wall 24 of a U-shaped supporting bar 25 located with its side flanges 26 on the outer side of the side walls 11 of the housing and embracing the lower edges of these side walls, and secured to the housing by the transverse pins or rivets 23.

Enclosing the front edges of the side walls 11 of the housing and also the front wall 14 of the inner housing 13 is a front plate or closure 27 which is of substantially U-shape in cross section, with side walls 28 at the outer sides of the side walls 11, and a front wall 29 against the forward edges of the side walls 11 but spaced from the front wall 14 of the inner housing to form a guide or raceway 30 for the staple driver 31. The intermediate portions of the front wall 29 of the member 27 may be offset outwardly, as shown in Figs. 1 and 2, to provide for clearance of the end of an operating spring 32 and also clearance for the end 33 of an operating pawl 34 carried by the operating lever 35.

The staple driver 31 is preferably an elongated flat strip of steel running in the guide or raceway 30, and it is provided with a pair of spaced openings 36 and 37 providing shoulders to be engaged by the operating spring 32 and the end 33 of the pawl 34. The spring 32 is preferably a round rod with its rearward end rigidly mounted on any suitable stationary part of the machine. In the present case it is mounted by means of one or more rivets 38 on an insert member 39 secured in the rear end of the upper guide member 22. The forward end of the upper wall of this member 29 may be extended upwardly, as shown at 40, and provided with an opening through which this spring rod extends, and which cooperates with the rivet or rivets 38 to center and position the rod. As shown in Fig. 1, the forward end of this rod passes through the opening 33 in the staple driver 31 for operating this driver, as will presently be described. The rod normally rests on the upper end of a resilient stop or bumper 41 mounted in the upper guide 22, and this stop or bumper may be of any suitable material, preferably live rubber or the like.

The operating lever 35 is preferably formed of sheet metal of suitable gauge, and the handle curved to substantially U shape in cross section, with side flanges extended to form side arms 42 located at the inner sides of the side members 13 of the inner housing 12 and pivoted thereto by a transverse pivot pin 43. The sides may be extended forwardly as indicated at 44 to form a stop means to engage the top wall 45 of the front plate 27 to limit the upward movement of the operating lever. The releasable pawl 34 is mounted in the lever between the side arms 42. This is preferably a flat plate of steel of relatively heavy gauge or thickness, and is provided with a longitudinal slot 46 through which the pivot pin 43 extends

and through which also extends a guide pin 47 spaced forwardly from the pin 43 and carried by the side walls 42 of the lever. These two pins in the slot 44 mount this pawl in the lever for longitudinal bodily sliding movement toward and from the staple driver 31 and the operating shoulder in this driver at the top of the opening 37. A spring 48 in the slot resting at its opposite ends against the forward end of the slot and the pin 47, tends to slide the pawl forwardly, this movement being limited by the pin 43 engaging the inner end of the slot. In the normal position, or the position of Fig. 1, the forward end 35 of the pawl extends into the opening 37 in the staple driver 31 and under the shoulder at the upper end of this opening. On the forward edge of the pawl above the extension 33 this pawl is provided with an inclined cam surface 49 adapted to cooperate with a transverse stationary member 50 mounted in the inner housing 12 to retract the pawl from the opening 31 to release the staple driver 31 after it has been raised to its upper or retracted position. The member 50 could be a block or transverse pin, but is preferably a roller on a transverse pin 51, so as to reduce the friction of operation and also wear on the cam surface. A portion of the forward edges of the side arms 42 of the lever may be extended inwardly, as shown at 52, to provide guides at the opposite sides of the pawl to retain it in a central position.

A spring is provided to return the lever 35 to and retain it in its normal position of rest, while the staple driver 31 is in its lowermost position. In the present case this is a wire spring 53 having a loop 54 at its forward end seated over a hook-shaped lug 55 projecting rearwardly from the front wall 14 of the inner housing, and is mounted by an intermediate loop 56 embracing a transverse pin 57, the free ends 58 of the wire resting against a transverse pin 59 at the lower ends of the side arms 42 to swing the lever to its upper position.

At the forward end of the staple guide bar 20 is a guide plate or block 60 provided with side flanges 61 embracing the forward ends of the side flanges 26 of the U-shaped member 25. As shown in Fig. 9, the forward edge of each side flange 26 is provided with a notch 62 into which an inwardly extending lug or pin 63 carried by the side flanges 61 of the block are seated and which hold the block or plate 60 in position. The intermediate portion of this block or plate is offset forwardly, as shown at 64, and forming spaced shoulders 60a engaging the front edges of the side walls 11 and 26, so that the intermediate portion 64 is spaced from the forward end of the staple feed bar 20 substantially the thickness of the staple driver 31 to form a continuation of the guide or raceway 30 at its lower end and cooperably with the forward end of the staple guide bar 20 to guide the staples during the staple driving operation, and also to guide the lower end of this driver 31 during this operation. This plate or block is held against the forward ends or edges of the side members 11 and 26 by a spring plate 65 pivoted to the front wall 29 at 66 having a lower arm 67 pressing against the outer surface of the block 60 to hold it in position. This spring finger may be provided with a lug 68 seating in an opening 69 in the block to yieldingly hold the spring in this position, but will force the lower arm 67 outwardly when the spring 65 is swung laterally on its pivot 66 to release the plate or block 60 and permit its removal from the machine to expose the front end of the staple guide

bar 20. Thus, should a staple become jammed in the lower end of the raceway or guide for the staple driver, plate or block 60 may be readily removed to permit removal of the jammed staple.

Means is provided for feeding the staples along the bar 20 to bring them successively to the driving position in the guide or raceway 30 under the staple driver 31. This comprises a substantially U-shaped follower 70 resting on the top of the bar 20 and engaging the rear end of the staple strip 71 to feed it forwardly along the bar. It is fed forwardly by means of a coil spring 72 embracing a guide rod 73 slidably secured at its forward end to the follower 70 by any suitable means, such as the loop 74 secured to the top wall of the follower. The inner end of the rod is enlarged or headed at 73a to prevent the follower being slid off the rod by the spring. The other end of this rod is connected at 75 to the end wall 76 of a block 77 of inverted U-shape in cross section, preferably formed from sheet metal, and carrying on the underside of its top wall a spring catch 78 carrying an upwardly projecting lug 79 adapted to seat in an opening 80 in the top wall of the insert member 39, the forward end 81 of the spring being curved downwardly so as to have a camming action on the end of the top wall of member 39 to force it downwardly when the block 77 is inserted in the end of the member 25. The push button 82 carried by this spring 78 projects through an opening in the top of the member 77 for depression of the spring 78 to release the catch 79. Adjacent this forward end the follower 70 may have a downwardly extending lug 83 lanced and bent downwardly from its top wall to engage the front cross wall 84 at the end of the staple guide 20 to limit forward movement of the follower when the last staple has been driven and prevent the end of the follower moving into a position under the staple driver 31.

In operation the parts are normally substantially in the position of Fig. 1. Depression of the lever 35 downwardly or to the right, as indicated by the arrow 85, will through the action of the pawl 34 raise the staple driver 31 to substantially the position of Fig. 6, carrying with it the spring rod 32 to substantially the dotted line position of Fig. 1. This will tension the spring 32 and will raise the lower end portion of the driver 31 from its position in front of the staple guide bar 20, permitting the forward staple 71a to move into the lower end portion of the guide and raceway 30 under the lower end of the driver 31 and into the driving position. As the lever 35 approaches its lower position carrying the pawl 34 to its upper position, as shown in Fig. 6, the stationary member 50 engages the cam surface 49 and shifts the pawl to the right, withdrawing its end 33 from the opening 37 in the staple driver 31 and from the shoulder at the top of this opening. This releases the driver 31, permitting the spring rod 32 to operate it downwardly to drive the staple. Downward movement of the driver 31 and rod 32 will be arrested by the resilient bumper and stop 41. Release of the handle 35 will permit it to be swung backwardly to the normal position of Fig. 1 by action of the spring 53. This will carry pawl 34 downwardly until its forward end 33 again snaps into the opening 37 in the driver preparatory to the next operation.

It is to be especially noted that the spring 32 is connected directly to the staple driver 31, and that this driver comprises only the elongated flat steel strip, and that there is no weight or plunger or any other element connected to this driver

to add weight to it and add momentum for a hammer blow, as is common with present types of machines of this character. Therefore, the weight of the driver and its inertia or momentum is reduced to a minimum as there is very little weight to the flat strip 31. Therefore, this driver is operated with much greater speed than is possible with the old type of driver, which includes a weighted plunger or similar carrying device for the driver, the inertia of such a device greatly slowing up the speed of operation of the driver, and the momentum or weight of the plunger or carrier for the driver is relied on to give a hammer blow to the staple to drive it at the end of the driving operation. With such a device a heavy spring is required and the speed of driving the staple is very much slower than in the present device, and the weight or momentum of the carrier or plunger for the driver is relied on to a large extent to drive the staple and secure the necessary penetration of the prongs of the staple. In the present construction, because of the minimum weight and momentum of the driver 31, there is no blow or momentum of the weighted element relied on, but a greatly increased speed of operation of the driver and driving action of the staple is secured over the old devices, this speed of operation securing better penetration of the prongs of the staple and, due to this much greater speed of the driving action and therefore the much greater speed of the penetration of the prong, there is much less danger of the prongs folding or buckling during the driving operation, as they do not have time to buckle as they do in the old type of device. It has been found that speed is more important than weight or momentum in properly and effectively driving the staples. This arrangement also simplifies the construction and tends to lightness or less weight. Also, as a lighter operating spring may be used, it is much more easily operated and less pressure is required in depressing the operating lever preparatory to the staple driving operation. Operation of this device is, therefore, much less tiring on the operator, and it may be used continuously much longer without fatigue.

The driver retracting and release construction comprising the bodily slidable pawl 34 is also a material improvement over the old type of construction involving merely a pivoted pawl depending on a runout of this pivoted pawl for the release. In this case a more substantial support is provided by the pawl, and as there is a positive shifting of the pawl for the release by means of the stop 50 and the cam 49, and therefore a positive release at a certain time, the release can be more accurately and reliably controlled, insuring that the driver is not released until it is retracted to the proper position.

In loading more staples into the machine, it is merely necessary to release the catch 79 by depressing the button 82 and withdrawing the block 77 and the follower 70. After the new staple strip is inserted on the guide bar 20 the follower is also inserted from the rear end onto this bar and the block 77 moved inwardly until caught by the catch 79, thus compressing the feed spring 72 and tensioning it so it may feed the staples forwardly.

Should for any reason a staple become jammed under the driver 31 in the lower part of the raceway 30, the spring strip 65 may be swung laterally 75 to release the plate or block 60, which may then

be removed to permit the jammed staple to drop out.

Having thus set forth the nature of my invention, what I claim is:

1. A staple driving machine comprising a guide bar for a strip of staples, a substantially flat staple driver mounted for reciprocating movement across the front end of the guide bar to drive the individual staples in succession, a spring comprising a rod fastened at one end and at the other directly engaging the driver for operating it to drive the staples, a pivoted operating lever, and a releasable pawl carried by the lever normally engaging the driver to retract it to tension the spring and then release the driver for the driving operation.

2. A staple driving machine comprising a guide bar for a staple strip, a staple driver mounted for movement across the end of the bar to drive a staple, means for feeding the staples along the bar to driving position, a spring rod fastened at one end and at its other end engaging a shoulder on the driver to operate it, a pivoted operating lever, and a releasable pawl on the lever engaging a shoulder on the driver to retract the driver to tension the spring and then release the driver for the staple driving operation.

3. A staple driving machine comprising a guide bar for a staple strip, a staple driver mounted for movement across the end of the bar to drive a staple comprising a substantially flat elongated strip, means for feeding staples along the bar to driving position, a spring rod fastened at one end and at its other end engaging a shoulder on the driver to operate it, a pivoted operating lever, a releasable pawl on the lever engaging a shoulder on the driver to retract the driver to tension the spring and then release the driver for the staple driving operation, and a resilient bumper under the spring to limit forward movement of the spring.

4. A staple driving machine comprising a guide bar for a strip of staples, a driver consisting of a light weight substantially flat elongated strip mounted for movement across the end of the bar to drive a staple, means for feeding staples along the bar to driving position, a spring comprising a rod fastened at one end and at the other directly engaging the driver strip to operate it, an operating lever, and a releasable pawl on the lever engaging the driver strip to retract it to tension the spring and then release the driver strip for the driving operation.

5. A staple driving machine comprising a guide bar for a strip of staples, a driver consisting of a light weight substantially flat elongated strip of substantially the same thickness throughout mounted for movement across the end of the bar to drive a staple, said strip being provided with vertically spaced shoulders, a spring comprising a rod fastened at one end and engaging one of said shoulders at the other end to operate the driver to drive a staple, an operating lever, and a releasable pawl on the lever engaging the other shoulder to retract the driver and tension the spring and then release the driver for the driving operation.

6. A staple driving machine comprising a guide bar for a strip of staples, a driver consisting of a substantially flat elongated strip mounted for movement across the end of the bar to drive a staple, said strip being provided with spaced shoulders, a spring rod fastened at one end and at its other end engaging one of said shoulders to operate the driver, an operating lever, and a re-

leasable pawl on the lever engaging the other shoulder to retract the driver to tension the spring and then release said driver for the driving operation.

5. 7. A staple driving machine comprising a guide bar for a strip of staples, a driver consisting of a substantially flat elongated strip mounted for movement across the end of the bar to drive a staple, said strip being provided with spaced shoulders, a spring rod fastened at one end and at the other end engaging one of said shoulders to operate the driver, means engaging the other shoulder to retract the driver to tension the spring and then release said driver for the driving operation, and a resilient bumper under the spring rod to limit the driving movement.

8. A staple driving machine comprising a guide bar for a staple strip, a staple driver mounted for movement across the end of the bar to drive a staple, means for feeding the staples along the bar to driving position, a spring engaging the driver for operating it, an operating lever, a pawl on the lever engaging a shoulder on the driver to retract it to tension the spring, cooperating guide means on the pawl and lever mounting the pawl for bodily sliding movement on the lever forwardly toward and rearwardly from the shoulder, a spring tending to shift the pawl toward the shoulder, and cooperating cam means to shift the pawl backwardly from said shoulder to release the driver as it approaches its retracted position.

9. A staple driving machine comprising a guide bar for a staple strip, a staple driver mounted for movement across the end of the bar to drive a staple, means for feeding the staples along the bar to driving position, a spring engaging the driver for operating it, a shoulder on the driver, an operating lever, a releasable pawl engaging said shoulder and mounted on the lever for bodily sliding movement toward and from the shoulder, said pawl being adapted to retract the driver to tension the spring by operation of the lever, a spring tending to hold the pawl in engagement with the shoulder, a cam surface on the pawl, and a stationary member positioned to engage the cam to shift the pawl from the shoulder to release the driver as it approaches the retracted position.

10. A staple driving machine comprising a guide bar for a staple strip, a staple driver mounted for movement across the end of the bar to drive a staple, means for feeding the staples along the bar to driving position, a spring engaging the driver for operating it, an operating lever, a pawl engaging a shoulder on the driver to retract the driver and tension the spring by operation of the lever, said pawl being provided with an elongated slot, spaced pins in the lever passing through the slot to mount the pawl for sliding movement toward and from the shoulder, a spring tending to shift the pawl to engage said shoulder, a cam surface on the pawl, and a stationary member positioned to engage said cam surface to shift the pawl to release the driver as it approaches its retracted position.

11. A staple driving machine comprising a guide bar for a staple strip, a staple driver mounted for movement across the end of the bar to drive a staple, means for feeding the staples along the bar to driving position, a spring engaging the driver for operating it, an operating lever including a pair of laterally spaced arms, a pawl mounted between said arms and engaging a shoulder on the driver to retract the driver

and tension the spring by operation of the lever, said pawl being provided with an elongated slot, spaced pins extending between the arms of the lever and through said slot to guide the pawl for sliding movement toward and from the shoulder, a spring in the slot tending to shift the pawl toward said shoulder, and cooperating cam means on the pawl and a stationary member to shift the pawl to release the driver as it approaches its retracted position.
